GEORGE I. KENISTON, OF TAFT, CALIFORNIA

WELL PUMPING APPARATUS

Application filed November 4, 1930. Serial No. 493,437.

My invention relates to and has for a purpose the provision of a mechanism of simple and rugged construction, which in its association with a conventional form of pumping apparatus embodying the usual engine, belt and band wheel drive, enables the pump to be driven from the engine at a relatively slow speed sufficing to successfully elevate a maximum quantity of oil from a low producing well, all while maintaining an engine speed sufficiently high for the engine to develop power efficiently, to the end that the power required for pumping will be conserved, and the wear on moving parts of the apparatus reduced to a minimum so that a low producing well can be profitably worked.

It is a further purpose of my invention to provide a mechanism of the above described character specifically embodying chain and sprocket speed reduction means preferably applied to the jack post and operatively connecting the band wheel shaft and the crank for actuating the walking beam in such manner that the rotational speed of the crank will be sufficiently reduced for the walking beam to operate the pump slowly while the normal operating speed of the engine is maintained.

I will describe only one form of well pumping apparatus embodying my invention, and will then point out the novel features thereof in claims.

In the accompanying drawings:

Figure 1 is a view showing in side elevation a conventional well pumping apparatus with one form of mechanism embodying my invention applied thereto.

Figure 2 is an enlarged view of the driving mechanism in side elevation.

Figure 3 is a view of the mechanism in end elevation.

Figure 4 is a vertical sectional view taken on the line 4-4 of Figure 3 and looking in the direction of the arrows.

Figure 5 is a horizontal sectional view taken on the line 5-5 of Figure 2.

Referring specifically to the drawings in which similar reference characters designate similar parts in each of the several views, my invention in its present embodiment is

shown associated with a standard form of well rig having a derrick 10 supported on a floor 11. A walking beam 12 is pivotally mounted on a Samson post 13 and is connected to sucker rods 14 working in the well tubing 15. The walking beam 12 is oscillated to reciprocate the sucker rods by means of a band wheel shaft 16 which is usually journaled on jack posts 17 and operatively connected by a crank 18 and pitman 19 to the walking beam. The band wheel 20 which is fixed to the shaft 16, is driven by an engine 21 through the medium of a belt 22 trained about the band wheel.

In the present instance the mechanism embodying my invention is interposed between the band wheel shaft 16 and the crank 18, and comprises a bracket A of substantially L shape having a horizontal portion 23 seating on the top of the jack post and a vertical portion 24 recessed into a vertical side of the jack post. Webs 25 rigidly connect the portions 23 and 24 and are also recessed into opposite sides of the jack post so as to be flush therewith.

The portion 23 of the bracket A is provided with a bearing B in which is journaled the band wheel shaft 16. The bearing B is constructed of lower and upper sections 26 and 27, the section 26 being formed integral with the bracket, and the section 27 providing the upper half or cap secured to the lower section by threaded studs 28 and nuts 29 thereon.

A second bearing B' is provided on the jack post and is supported on the vertical portion 24 of the bracket A parallel to the bearing B. A countershaft 30 is journaled in the bearing B' by means of anti-friction roller units 31 seating in pockets in the bearing B' and retained against displacement by rings 32 secured to the bearing by screws 33.

The countershaft 30 projects from opposite ends of the bearing B' and has fixed thereto the crank 18 provided with the usual wrist pin 34 working in a slot 35 of the pitman 19. Fixed to the band wheel shaft 16 which constitutes a drive shaft, is a sprocket wheel 36; and fixed to the countershaft 30 is a second sprocket wheel 37 larger than the wheel 36.

A chain 38 is trained about the sprocket wheels 36 and 37 so that when the band wheel shaft is rotated by the engine, the counter-shaft and hence the crank 18 will be driven at a reduced speed and thus reciprocate the sucker rods to actuate the pump at a relatively slow speed while the engine is operating at a relatively high and efficient speed as is necessary in order to obtain the required amount of power.

In the present instance the bearing B' is slidably mounted on the vertical portion 24 of the bracket A for adjustment towards and away from the bearing B, by the provision of rectangular and alined projections 39 on the bearing slidably fitting into a slot 40 formed in the bracket. The bearing B' is provided with slots 41 receiving tie members in the form of bolts 42 having nuts 43, the bolts extending through registering openings in the vertical portion 24 of the bracket and jack post so that when the nuts are tightened they co-act with the bolts to perform the dual function of securing the bearing B' in a selected position of adjustment relative to the bearing B and to secure the bracket A to the jack post.

The adjustability of the bearing B' enables slack in the chain 38 to be removed and sufficient tension placed upon the chain for the latter to operate at maximum efficiency; and to permit of such adjustment of the bearing B' with the utmost ease and dispatch, a feed screw 44 is journaled at one end in a sleeve 45 formed on the bracket A, and at its other and reduced end 46 in a second sleeve 47 also formed on the bracket in alinement with the first sleeve. The feed screw extends freely through an opening in the bearing B' and is threaded through a nut 48 secured to the bearing B' by screws 49 so that by applying a wrench or other tool to an angular head 50 on the feed screw, and rotating the latter in one direction when the nuts 43 of the bolts 42 are loosened, the bearing B' can be readily moved away from the bearing B until the desired tension upon the chain has been obtained.

Hold down members in the form of tie bolts 51 extending at their upper ends through lugs 52 on the lower end of the bracket A and provided thereat with nuts 53, are secured by other nuts 54 to a tie plate 55 extending beneath the mud sill 56 on which the jack post rests. The tie bolts 51 co-act with a third tie bolt 57 also extending through a lug 58 on the bracket, and connected to the latter, bearing section 27, and to the tie plate 55 by nuts 59 and 60 respectively, to fixedly secure the jack post to the mud sill or foundation, as well as secure the bracket on the jack post as will be understood. In addition the jack post is braced by brace rods 61.

With the mechanism embodying my invention applied to the pumping apparatus as

above described, it will be manifest that when the engine is in operation, the rotational speed of the crank 18 will be sufficiently reduced relative to the rotational speed of the band wheel shaft 16, to enable the engine to be operated at a relatively high speed commensurate with maximum efficiency, while actuating the pump at a relatively slow speed which may be as little as a few strokes per minute. Thus in pumping wells from which oil is available in small quantities capable of being elevated as a result of a relatively slow pumping speed, the conservation of power as well as a reduction in the wear of the working parts of the pumping apparatus will be effected by the use of my invention.

Although I have herein shown and described only one form of well pumping apparatus embodying my invention, it is to be understood that various changes and modifications may be made therein without departing from the spirit of the invention and the spirit and scope of the appended claims.

I claim:

1. In well pumping apparatus, a jack post, a substantially L shaped bracket having one portion provided with a bearing and overlying the top of the jack post and another portion overlying a vertical side of the jack post, a drive shaft journaled in the bearing, a second bearing on the second portion of the bracket, a countershaft journaled in the second bearing, a driving connection between the shafts, means for slidably mounting the second bearing on the second portion of the bracket parallel to the first bearing for adjustment relative to the latter to compensate for variations in the driving connection, and means for securing the second bearing in a selected position of adjustment.

2. In well pumping apparatus, a jack post, a substantially L shaped bracket having one portion provided with a bearing and overlying the top of the jack post and another portion overlying a vertical side of the jack post, a drive shaft journaled in the bearing, a second bearing on the second portion of the bracket, a countershaft journaled in the second bearing, a driving connection between the shafts, means for slidably mounting the second bearing on the second portion of the bracket parallel to the first bearing for adjustment relative to the latter to compensate for variations in the driving connection, and tie members extending through the second bearing, second portion of the bracket and jack post, for securing the bracket to the latter and the second bearing in a selected position of adjustment on the bracket.

3. In well pumping apparatus, a jack post, a substantially L shaped bracket secured to the jack post and having one portion overlying the top of the latter and another portion overlying a vertical side of the jack post, a bearing on the first portion of the bracket,

- 1 a band wheel shaft journaled in the bearing, a second bearing, co-acting means on the second portion of the bracket and the second bearing for mounting the latter on the 5 bracket for adjustment relative to the first bearing, a countershaft to which a crank is adapted to be fixed, journaled in the second bearing parallel to the first shaft, a sprocket wheel fixed to the first shaft, a second sprocket 10 wheel larger than the first sprocket wheel, fixed to the countershaft, a chain trained about the sprocket wheels, and means for securing the second bearing in any selected position of adjustment.

15 4. In well pumping apparatus, a jack post, a substantially L shaped bracket secured to the jack post and having one portion overlying the top of the latter and another portion overlying a vertical side of the jack post, 20 a bearing on the first portion of the bracket, a band wheel shaft journaled in the bearing, a second bearing, co-acting means on the second portion of the bracket and the second bearing for mounting the latter on the 25 bracket for adjustment relative to the first bearing, a countershaft to which a crank is adapted to be fixed, journaled in the second bearing parallel to the first shaft, a sprocket wheel fixed to the first shaft, a second sprocket 30 wheel larger than the first sprocket wheel, fixed to the countershaft, a chain trained about the sprocket wheels, and tie bolts extending through the second bearing, second portion of the bracket and jack post, for securing the bracket to the jack post and the second bearing in a selected position of adjustment.

35 5. In well pumping apparatus, a jack post, a substantially L shaped bracket secured to the jack post and having one portion overlying the top of the latter and another portion overlying a vertical side of the jack post, 40 a bearing on the first portion of the bracket, a band wheel shaft journaled in the bearing, a second bearing, co-acting means on the second portion of the bracket and the second bearing for slidably mounting the latter on the bracket for adjustment relative to the first bearing, a countershaft to which a crank 45 is adapted to be fixed, journaled in the second bearing parallel to the first shaft, a sprocket wheel fixed to the first shaft, a second sprocket wheel larger than the first sprocket wheel 50 fixed to the countershaft, a chain trained about the sprocket wheels, a feed screw journaled in the bracket, a nut secured to the second bearing co-acting with the feed screw to adjust the second bearing in response to rotation of the feed screw, and means for securing the second bearing in any selected position of adjustment.

55 6. In well pumping apparatus, a jack post, a substantially L shaped bracket secured to the jack post and having one portion overlying the top of the latter and another portion overlying a vertical side of the jack post, 60 a bearing on the first portion of the bracket, a band wheel shaft journaled in the bearing, a second bearing, co-acting means on the second portion of the bracket and the second bearing for slidably mounting the latter on the bracket for adjustment relative to the first bearing, a countershaft to which a crank 65 is adapted to be fixed, journaled in the second bearing parallel to the first shaft, a sprocket wheel fixed to the first shaft, a second sprocket wheel larger than the first sprocket wheel fixed to the countershaft, a chain trained about the sprocket wheels, a feed screw journaled in the bracket, a nut secured to the second bearing co-acting with the feed screw to adjust the second bearing in response to rotation of the feed screw, and means for securing the second bearing in any selected position of adjustment.

70 7. In well pumping apparatus, a jack post, a substantially L shaped bracket having one portion provided with a bearing and overlying the top of the jack post and another portion overlying a vertical side of the jack post, webs overlying other vertical sides of the jack post and rigidly connecting said portions of the bracket, a shaft journaled in the bearing, a second bearing on the second portion of the bracket, a shaft journaled in the second bearing, and a driving connection between the shafts.
